F. HACHMANN.

CLAMP.

APPLICATION FILED MAR. 15, 1920. RENEWED MAY 11, 1921.

1,391,828.

Patented Sept. 27, 1921.

UNITED STATES PATENT OFFICE.

FREDERICK HACHMANN, OF ST. LOUIS, MISSOURI, ASSIGNOR TO WILLIAM H. GREGG,
TRUSTEE, OF ST. LOUIS, MISSOURI.

CLAMP.

1,391,828.

Specification of Letters Patent. Patented Sept. 27, 1921.

Application filed March 15, 1920, Serial No. 365,938. Renewed May 11, 1921. Serial No. 468,728.

To all whom it may concern:

Be it known that I, FREDERICK HACHMANN, a citizen of the United States of America, a resident of the city of St. Louis, 5 in the State of Missouri, have invented certain new and useful Improvements in Clamps, of which the following is a full, clear, and exact description, reference being had to the accompanying drawings, forming

10 a part of this specification.

This invention relates to improvements in clamps, one of the objects being to produce a strong and simple clamp having a firm thrust-receiving bearing for a clamping screw. More specifically stated, the preferred form of the invention comprises a novel combination of elements whereby a simple thrust-receiving member is securely anchored in a yoke, to which the stresses are 15 transmitted from the clamping screw. This thrust-receiving member is preferably a tube threaded to receive the clamping screw and preferably interlocked with the yoke, so as to effectively withstand the stresses to which 20 it is subjected.

Figure I is a side elevation, partly in section, illustrating a clamp embodying the features of this invention.

Fig. II is a front elevation of the clamp. 30 Fig. III is a vertical section illustrating the thrust-receiving sleeve anchored in the yoke.

Fig. IV is a horizontal section taken approximately on the line IV—IV, Fig. III, 35 the projections at the lower end of the sleeve being shown in elevation.

Fig. V is a section on line V—V, Fig. III.

To illustrate the invention, I have shown a yoke comprising oppositely disposed 40 thrust arms A and B, and a connecting member C uniting said arms. The elements of this yoke include a continuous web having a horizontal upper member 1, a horizontal lower member 2 and a vertical member 3. Flanges 4 extend from the side margins of the continuous web, said flanges being combined with the web to form a continuous yoke, channel shaped in cross section.

50 At the end of thrust arm A, the web 2 is extended and turned downwardly and backwardly between the flanges 4, as indicated at 2^a and 2^b, the downturned member 2^a being

between end margins of the flanges 4 and the member 2^b being between the lower margins of said flanges. Apertures 5 are formed in said lower margins, and the web member 2^b is provided with lateral projections 6 which extend into said apertures. The extended end portion 2^b of the web is thus interlocked with and securely anchored in the flanges 4.

A threaded thrust-receiving sleeve D is arranged between the flanges 4 of the lower arm A and also between the horizontal web 2 and the end portion of its extension 2^b. The bottom face of the sleeve or tube D is seated upon the end portion 2^b of the web, while the upper portion of said sleeve is seated in a circular opening in the web 2. The upper end of thrust-receiving sleeve D is turned outwardly to form a flange 7 seated upon the face of the web member 2. At its lower end, the sleeve D is provided with lateral projections 8 extending into the apertures 5 and seated upon the projections 6 of the web member 2^b.

The yoke is preferably made of thin pressed metal, and the sleeve D is inserted into arm A while its flanges 4 are separated a distance great enough to receive the projections 6 and 8. Thereafter, these flanges 4 are forced toward each other for the purpose of locating the projections 6 and 8 in the apertures 5.

9 designates a clamping screw mounted in the threaded sleeve D and having a head 10 at its lower end and a seat 11 at its upper end. When the clamp is in service, the screw 9 is tightened and the sleeve D is subjected to a thrust in a downward direction from the position shown by Figs. I and III. Owing to the manner in which the sleeve D is combined with other elements of the clamp, the thrusts tending to displace the sleeve 95 are firmly opposed by the anchored web member 2^b on which the bottom of the sleeve is seated, and also by the flanges 4 with which the sleeve projections 8 are securely interlocked and the web member 2 on which the flange 7 at the upper end of the sleeve is seated. In addition to firmly resisting the thrusts, the anchoring means for the sleeve prevent displacement thereof in any direction, and the appearance of the article is improved by the extended web por-

tions 2^a and 2^b, which coöperate with web 2 and flanges 4 to form a housing for the thrust-receiving sleeve.

I claim:

- 5 1. A clamp comprising a yoke having oppositely disposed thrust-receiving arms, one of said arms being in the form of a channel having a web and marginal flanges extending therefrom, a threaded thrust-receiving 10 tube between said flanges, said web having an extended end portion turned downwardly and backwardly to form a seat for one end of said thrust-receiving tube, and a clamping screw mounted in said thrust-receiving 15 tube.
2. A clamp comprising a yoke having oppositely disposed thrust-receiving arms, one of said arms being in the form of a channel having a web and marginal flanges extending 20 therefrom, a threaded thrust-receiving tube arranged between said flanges and having its upper portion seated in said web, said web being extended downwardly and backwardly between said flanges to form a seat 25 for the lower end of said tube, the extended portion of said web being interlocked with

and secured to said flanges, and a clamping screw mounted in said thrust-receiving tube.

3. A clamp comprising a yoke having oppositely disposed thrust-receiving arms, said 30 yoke consisting of a web and side flanges extending therefrom to form a channel shape in cross section, said web having an extended portion turned downwardly and backwardly between the margins of the flanges at the 35 outer end of one of said arms, said flanges being provided with apertures and the end of said extended portion of the web being provided with lateral projections anchored in said apertures, a threaded sleeve arranged between the apertured flanges and having its upper end turned outwardly and seated on the face of the web, the lower end of said sleeve being seated on the extended end portion of said web and provided with 40 lateral projections anchored in said apertures, and a clamping screw mounted in said 45 threaded sleeve.

In testimony that I claim the foregoing I hereunto affix my signature.

FREDERICK HACHMANN.
